UNITED STATES PATENT OFFICE.

GEORGE W. SHERIDAN, OF WINTHROP, MASSACHUSETTS.

EXERCISING DEVICE.

1,189,396.

Specification of Letters Patent.

Patented July 4, 1916.

Application filed October 14, 1915. Serial No. 55,877.

To all whom it may concern:

Be it known that I, GEORGE W. SHERIDAN, a citizen of the United States, residing at Winthrop, in the county of Suffolk and State of Massachusetts, have invented an Improvement in Exercising Devices, of which the following is a specification.

The present invention relates to an improved exercising device, and is especially designed for developing the muscles of the wrist and forearm, although all of the muscles of the hands and arms are more or less brought into action.

The essential object of the invention is to provide a simple and effective device of this character which may be readily and easily adjusted, to adapt it for use by persons of different strength, and to vary the amount of strength required to operate it.

Structurally speaking, the invention consists of an exerciser having relatively movable operating-members adapted to be engaged by the hands, yielding-means associated with one of said members including a spring, and movable controlling-means associated therewith and connected with the other member, adapted for operation by a movement of the members toward each other to compress the spring and bring the movable controlling-means into alining position, and locking-means, preferably provided, which is associated therewith by which the parts become locked in alining position.

More specifically speaking, my invention involves adjusting-means for the yieldable means by which it may be adjusted to require a greater or lesser force to compress its spring. It also involves a movable controlling-means consisting of one or more struts adapted to be arranged between a fixed bearing point and the yieldable means, and to be brought into alining position by a movement of the hand-engaging members toward each other.

It also involves a movable controlling-means consisting of a universally-jointed element comprising two universally-engaging struts, adapted to be normally held by the spring out of alining position, one of said struts being connected with one of the hand-engaging members, by which said element may be moved into alining position upon movement of the two hand-engaging members toward each other. The locking-

means may be associated with the strut or struts, and may be constructed and arranged to slide or to be otherwise moved into engagement with one of the operating-members.

The above, and other incidental objects of a similar nature, are accomplished by such means as are illustrated in the drawings, described in the following specification, and then more particularly pointed out in the claims which are appended hereto, and form a part of this application.

Figure 1 is a longitudinal vertical section of an exerciser embodying this invention. Fig. 2 is a similar view of a modified form.

As embodied in Fig. 1, the exerciser comprises a hand-engaging member, shown as a tube 10, a helical spring 11, disposed longitudinally in the tube, an adjusting-screw 12 at the lower end of said tube for regulating the tension of the spring, a crown-piece mounted upon the upper end of said tube, co-acting struts 14 and 15 arranged to form a universally-jointed element, a bearing-screw 16 for the outer end of the strut 14, a bearing-plate 17 for the outer end of the strut 15, a hand-engaging member 33 arranged on the strut 14, preferably in an adjustable manner, and a locking-plate 18, which is slidably arranged upon the strut 14, and is spring-pressed to move into engagement with the upper open end of the tube when the hand-engaging members are manipulated against the tension of spring 11, to dispose the struts 14 and 15 in vertical alinement, as for instance, by a movement of said members toward each other.

The lower end of the tube 10 is internally threaded to receive the boss 19 of the closure-plug 20, through the center of which is threaded the adjusting-screw 12. The outer end of this screw has a wing-head 21, and the inner end has a reduced stem 22 freely received in a central opening 23 of a circular plate 24, which is slidable in the tube 10. A collar 25 is secured by a pin 26 to the inner end of a screw and serves as an abutment for the plate 24. Suitable indicia are or may be inscribed on the screw so that the user may readily ascertain the force, in pounds, which adjustment of the spring will exert against the alinement of the universally-jointed struts.

The crown-piece comprises an internally threaded collar 27, which is engaged with the exterior threaded end-portion of the tube 10, and a plurality (preferably three) of arcuate arms connected at their upper ends by a boss 28, said boss being disposed in the longitudinal axis of the tube. The bearing-screw 16 is inserted through this boss, and has at its inner end a substantially conical socket which receives the conical upper end of strut 14. The lower end of said strut 14 has a conical socket wherein is received the upper end of the strut 15, and the lower end of said strut 15 is also conical and is received in a conical socket formed in the bearing-plate 17, which is normally forced toward the upper end of the tube by the spring 11.

The strut 14 is threaded and received in a threaded sleeve-like socket 29, carried on the end of handle 33. Thus the handle may be adjusted longitudinally with respect to the strut for a purpose which will be hereinafter explained, and a set-screw 30 is provided for holding the handle in adjusted position on the pin. The thread of the strut 14 terminates short of the lower end of the strut to provide a smooth portion 31, upon which the locking-plate 18 is freely slideable. This plate is of a diameter greater than the internal diameter of the tube 10, but has on its under side a boss 32, which is of a diameter slightly less than the internal diameter of the tube, so that it may freely enter said tube. A weak spring 50 is arranged on the strut 14 between the socketed member 29 and the plate 18 which exerts its force on said plate.

The spring 11 being of expansive type, normally maintains the universally-jointed element broken by holding the struts 14 and 15 out of alignment. The movement of the struts within the tube is universal, and the distance which the engaging ends of the struts may move is limited by the wall of the tube 10.

In operation, the tube 10 and handle 33 are grasped by the two hands of the user, and are then relatively manipulated to bring the struts 14 and 15 into alignment and maintain them in this relation until the locking-plate 18 is moved by its spring 50 to dispose its boss 32 in the upper end of tube 10. As explained, the engagement of the boss 32 in the upper end of the tube will maintain the struts in alignment. The plate 18 may be lifted subsequently by the user so as to unlock or reset the device, whereupon the spring 11 will immediately act to again break the universally-jointed element, since the bearing point of the upper end of strut 15 is relatively unstable.

An essential feature of my invention is that the device may be adjusted for use by persons of different strengths in two dif-

ferent ways. First, the adjusting-screw 12 may be manipulated to vary the tension of the adjusting-spring. Second, the handle 33 may be adjusted longitudinally with respect to the strut 14 to dispose the socket 29 at different distances from the point of engagement of the two struts, thereby increasing or decreasing the leverage exerted through the handle to oppose the expansion of the spring.

While I prefer to employ the specific structural features herein shown, it is understood that many structural modifications are within the scope of my invention as long as the modified structure embodies two relatively movable hand-engaging members, and a controlling-element and means acting expansively to hold said element normally out of alignment position, and adapted to be moved by manipulation of the hand-engaging members.

In the modified form of the invention shown in Fig. 2, the exerciser is of somewhat simpler construction and includes essentially a hand-engaging body-tube 35, a crown-piece 36, a strut 37 having its upper end seated for universal movement in a bearing-screw 38, and having its lower end disposed for engagement with a disk 39, which is slideable in the body-tube 35, and is normally urged toward the open end thereof by an expansive helical spring 40. The tension of the spring 40 may be adjusted by a screw 43, equivalent to the adjusting-screw 12 of the preferred form.

In operation the strut is normally held out of alignment with the longitudinal axis of the tube since the locking-plate 18 is in its disengaging position, and the spring acts to cause the lower end of the strut to move toward the wall of the tube. The operating-member may, however, be manipulated relative to the body-tube to move the lower end of the strut over the face of the disk, into alignment with the tube, and enable the locking-plate to enter the upper open end of the tube.

I claim:—

1. An exerciser comprising relatively movable operating-members, a movable element controlled by one of the operating-members and movable relative to the other operating-member, a fixed universal bearing for one end of the movable element and yieldable means associated with the second-mentioned operating-member and exerting a thrust against the movable element for resisting the movement of the same into alignment with the path of movement of the said means.

2. An exerciser comprising relatively movable operating-members, a fixed bearing, a movable bearing associated with one of the operating-members, yieldable means acting to move the movable bearing toward the fixed bearing, and a movable member interposed

- between said bearings and terminally engaging them, and governed by the other operating-member, said yieldable means acting to normally maintain the movable member in 5 position with its axis at an angle to the path of movement of the movable bearing.
3. An exerciser comprising relatively movable operating-members, a fixed bearing associated with one of the operating-members, 10 a movable bearing associated with the first mentioned operating-member and movable relative to the operating-member, a member interposed between the bearings and terminally engaging them, said member being 15 movable with the second operating member, and yieldable means normally forcing the movable bearing toward the fixed bearing whereby the said member is normally yieldably maintained in position with its axis at 20 an angle to the path of movement of the movable bearing.
4. An exerciser comprising relatively movable operating-members, a movable element controlled by one of the operating-members 25 and movable relative to the other operating-member, a fixed universal bearing for one end of the movable element and yieldable means associated with the second-mentioned operating member and exerting a thrust against 30 the movable element for resisting the movement of the same into alinement with the path of movement of the said means, and locking-means effective when the movable element is brought into alining position.
5. An exerciser comprising relatively movable operating-members, a universally jointed element associated with said members, and a yieldable means opposing an alining movement of said jointed element. 35
6. An exerciser comprising relatively movable operating-members, a universally jointed element associated with said members and comprising two universally engaging-elements, and a yieldable means borne by one 40 of said members arranged to resist the alinement of the components of the jointed element.
7. An exerciser comprising relatively movable operating members, a universally jointed element associated with said members, and yieldable means including a spring arranged to oppose movement of the jointed elements, and means for adjusting the normal tension of said spring. 45
8. An exerciser comprising a body-member, an operating-member, a member slidably borne by the body-member, a universally jointed element comprising universally engaging struts, to one of which the operating-member is connected, and a yieldable means borne by the body-member and tending to normally move the same in a direction to maintain the members out of alinement and to oppose the alining of said struts. 55
9. An exerciser comprising a body-mem- 60 ber, a universally jointed element comprising universally engaging struts, a controlling-member connected to one of the struts, a slideable bearing borne by the body-member for one of the struts, and a yieldable member acting on the slideable bearing-member to normally maintain the struts out of alinement, and to oppose their movement into alining position. 70
10. An exerciser comprising a body tube, 75 an expansive spring arranged therein, a crown-piece, a bearing plate slideable in the tube and engaged by the spring, whereby it is normally projected in the direction of the crown-piece, a universally jointed element interposed between the crown-piece and bearing-member, and comprising universally engaging struts which are normally held out of alinement by the expansion of the spring, and a controlling-member connected to one 80 of the struts and movable relative to the tube for moving the struts into alinement against opposition of said spring. 85
11. An exerciser comprising a body tube, 90 an expansive spring arranged therein, a crown-piece, a bearing plate slideable in the tube and engaged by the spring, whereby it is normally projected in the direction of the crown-piece, a universally jointed element interposed between the crown-piece and bearing-member, and comprising universally engaging struts which are normally held out of alinement by the expansion of the spring, and a controlling-member connected to one 95 of the struts and movable relative to the tube for moving the struts into alinement against opposition of said spring, and means for adjusting the tension of the spring. 100
12. An exerciser comprising a body tube, 105 an expansive spring arranged therein, a crown-piece, a bearing-plate slideable in the tube and engaged by the spring, whereby it is normally projected in the direction of the crown-piece, a universally jointed element 110 interposed between the crown-piece and bearing-member, and comprising universally engaging struts which are normally held out of alinement by the expansion of the spring, and a controlling-member connected to one 115 of the struts and movable relative to the tube for moving the struts into alinement against opposition of said spring, and a locking element carried by one of the struts, engageable with the tube for locking the 120 struts in alinement.
13. An exerciser comprising a body tube, 125 an expansive spring arranged therein, a crown-piece, a bearing-plate slideable in the tube and engaged by the spring, whereby it is normally projected in the direction of the crown-piece, a universally jointed element interposed between the crown-piece and bearing-member, and comprising universally 130 engaging struts which are normally

held out of alinement by the expansion of the spring, and a controlling-member connected to one of the struts and movable relative to the tube for moving the struts into alinement against opposition of said spring, and means for adjusting the controlling-member longitudinally with respect to its strut.

14. An exerciser comprising a body-tube, 10 an expansive spring arranged therein, a bearing-member slidable in the tube, a crown-piece borne by the tube, a universally jointed element interposed between the crown-piece and the bearing-member 15 and comprising a pair of universally engaging struts, the outer end of one strut being engaged with the bearing member for universal movement with respect thereto, and a bearing screw carried by the crown-piece 20 for the outer end of the other strut, said struts being normally maintained out of alinement by the expansion of the spring, and a controlling-member connected to one 25 of the struts for moving said struts into alinement against opposition of the spring.

15. An exerciser comprising a body-tube, an expansive spring arranged therein, a bearing-member slidable in the tube, a crown-piece borne by the tube, a universally 30 jointed element interposed between the crown-piece and the bearing-member and comprising a pair of universally engaging struts, the outer end of one strut being engaged with the bearing member for universal movement with respect thereto, and a bearing screw carried by the crown-piece 35 for the outer end of the other strut, said struts being normally maintained out of alinement by the expansion of the spring, and a controlling-member connected to one 40 of the struts for moving said struts into alinement against opposition of the spring,

and a locking-element for maintaining the struts in alinement.

16. An exerciser comprising a body-tube, 45 an expansive spring arranged therein, a bearing-member slidable in the tube, a crown-piece borne by the tube, a universally jointed element interposed between the crown-piece and the bearing-member and 50 comprising a pair of universally engaging struts, the outer end of one strut being engaged with the bearing member for universal movement with respect thereto, and a bearing screw carried by the crown-piece for 55 the outer end of the other strut, said struts being normally maintained out of alinement by the expansion of the spring, and a controlling-member connected to one of the struts for moving said struts into alinement 60 against opposition of the spring, and a locking-element for maintaining the struts in alinement, said locking element being 65 slideable upon the strut and being arranged to fall by gravity into locking engagement with the body tube upon the alinement of the struts.

17. An exerciser comprising a tubular body member and operating-member yieldable means tending to normally hold 70 said members in a predetermined relation and opposing their movement into any other relation, a locking disk associated with said means movable into the open end of the tubular member to lock said member against 75 the force of the yieldable means.

In testimony whereof, I have signed my name to this specification, in the presence of two subscribing witnesses.

GEORGE W. SHERIDAN.
